UNITED STATES PATENT OFFICE.

SAMUEL HELLER, OF NEW YORK, N. Y.

DESIGN FOR A PRECIOUS OR SEMIPRECIOUS OR SYNTHETIC STONE OR AN IMITATION
THEREOF.

46,734.

Specification for Design.

Patented Dec. 8, 1914.

Application filed May 23, 1914. Serial No. 840,634. Term of patent 7 years.

To all whom it may concern:

Be it known that I, SAMUEL HELLER, a citizen of the United States, residing in the borough of Manhattan, in the city, county, and State of New York, have invented a new, original, and ornamental Design for a Precious or Semiprecious or Synthetic Stone or an Imitation Thereof, of which the following is a specification, reference being had therein to the accompanying drawings, which form a part thereof.

In the drawings: Figure 1 is a plan view of a cut stone embodying my design; Fig. 2 is a side view thereof; and Fig. 3 is an end view thereof.

Copies of this patent may be obtained for five cents each, by addressing the "Commissioner of Patents, Washington, D. C."

I claim:

The ornamental design for a precious, or semi-precious, or synthetic stone or an imitation thereof consisting of a flat table extending across the crown and having at the sides thereof four triangular facets, the base of one of said triangular facets being the table and of the other three, the girdle and a pavilion having facets thereon.

SAMUEL HELLER.
